UNITED STATES PATENT OFFICE

109,880

DESIGN FOR A RADIOPHASIC AND FLUOROSCOPIC UNIT

Alfred Simon, Jackson Heights, N. Y., assignor
to Westinghouse X-Ray Company, Inc., a cor-
poration of Delaware

Application September 1, 1937, Serial No. 71,413

Term of patent 14 years

To all whom it may concern:

Be it known that I, Alfred Simon, a citizen of the United States, residing in Jackson Heights, in the county of Queens and State of New York, have invented a new, original, and ornamental design for a Radiographic and Fluoroscopic Unit, of which the following is a specification, reference being had to the accompanying drawing, forming part thereof.

Fig. 1 is a perspective view of a radiographic

and fluoroscopic unit when viewed from one side thereof showing my new design; and

Fig. 2 is a perspective view of the unit when viewed from the opposite side and end shown in Fig. 1.

I claim:

The ornamental design for a radiographic and fluoroscopic unit substantially as shown.

ALFRED SIMON.
